UNITED STATES PATENT OFFICE.

THOMAS S. PARKER, OF SCHENECTADY, NEW YORK.

TRIMMING ATTACHMENT FOR SEWING-MACHINES.

SPECIFICATION forming part of Letters Patent No. 270,467, dated January 9, 1883.

Application filed September 28, 1882. (No model.)

To all whom it may concern:

Be it known that I, THOMAS S. PARKER, a citizen of the United States, residing at Schenectady, in the county of Schenectady and State 5 of New York, have invented certain new and useful Improvements in Trimming Attachments for Sewing-Machines; and I do declare the following to be a full, clear, and exact description of the invention, such as will enable 10 others skilled in the art to which it appertains to make and use the same, reference being had to the accompanying drawings, and to the letters and figures of reference marked thereon, which form a part of this specification.

15 This invention relates to mechanism for supporting, guiding, and trimming the edges of knit fabrics while the same are being stitched in a sewing-machine of suitable construction, the object being to provide a simple and improved means of adjusting and operating the cutting devices; and to this end the invention consists in certain peculiarities in the construction, arrangement, and combination of parts, as will be hereinafter more fully explained.

20 In the annexed drawings, illustrating the invention, Figure 1 is a vertical rear elevation of a sewing-machine provided with my improved trimming attachments, and showing the means for supporting, operating, and adjusting the movable knife. Fig. 2 is a plan of the machine. Fig. 3 is a detail perspective, showing the manner of arranging the stationary knife with relation to the movable knife 25 and presser-foot, and also the means for adjustably securing said stationary knife. Fig. 4 is an end view illustrating the form and position of the movable knife, presser-foot, and feed. Fig. 5 is a detail view of a portion of 30 the bracket-lever that supports one end of the vibratory lever for operating the movable knife; and Fig. 6 is a longitudinal section of the stationary knife, together with a portion of the bed or cloth plate and a transverse 35 section of the feed.

40 Like letters of reference are used to designate the same parts throughout the several views.

45 The trimming devices and means for adjusting and operating the same, as shown in

the drawings above referred to, are capable of being applied to any ordinary sewing-machine, but are particularly applicable to that class of machines employed in stitching knit fabrics, and in which it is desirable to trim the edges 55 of the fabric while being stitched.

Referring to the drawings, the letter A is used to designate the bed or cloth plate, and B is an adjustable bracket, that is supported upon the cloth-plate in any suitable manner, 60 so as to be readily adjusted by means of a set-screw, a, and slot b, as shown in Fig. 1, or by any other convenient means, for the purpose of altering the position of the movable knife, as hereinafter described. The bracket B is 65 provided with an irregularly T-shaped arm, c, to the forward end of which is attached a vertical sleeve or casing, d, for inclosing a vertically-reciprocating rod or bar, e, the lower end of which is enlarged or expanded to afford a bearing-surface for the attachment of the movable knife C, which is detachably secured to said expanded portion of the bar e by means of screws, as shown in Figs. 1, 3, and 4. The rod or bar e and its casing d may 70 be made rectangular, as shown, or they may be made cylindrical, if desired, being provided in the latter case with suitable means for preventing rotation of the bar or rod within its casing. One side of the sleeve or casing d is 75 preferably slotted longitudinally or provided with a detachable slotted plate, d', in order to afford a passage for the means of connecting the rod or bar e with its operating mechanism, which operating mechanism consists prefera- 80 bly of a vibratory lever, D, having a pivotal connection with an arm of the adjustable bracket B, as shown in Figs. 1, 2, and 3. This lever D may be operated from any moving part of a sewing-machine; but as shown in 85 the drawings it is operated from the looper-shaft E, as hereinafter described.

The forward end of the lever D has a pivotal connection with the vertically-moving knife-supporting bar e through a stud, screw, or 90 other suitable device, while its rear end is connected by a link, f, to a slotted segmental connection or plate, F, that is pivoted to a bracket-shaped lever, G, which is suitably connected to the actuating-arm H of the needle-bar, said 95 100

arm being vibrated by means of a link, I, connecting the arm with the looper-shaft in a well-known manner.

It will thus be seen that as the needle is operated to stitch the fabric the movable knife C will be reciprocated in contact with the cutting-edge of the stationary knife K for the purpose of trimming the edges of the fabric in a line parallel with the line of stitch, the fabric 10 at the same time being fed by means of the usual devices beneath the presser-foot L and in position to be acted upon by the stitching and cutting mechanism.

It will also be observed that the slotted segment F, which has a pivotal connection with the link f and lever G, may be adjusted by means of the slot f', screw g, and thumb-nut h, or other suitable devices, so as to raise or lower the link f and rear end of the lever D for 15 the purpose of regulating the vertical position of the movable knife C or for lowering the same to compensate for wear of its edge.

The stationary knife K consists preferably of a flat metallic bar or plate having one end 20 beveled to a cutting-edge, as shown in Fig. 6. This knife is provided with a stud or handle, k, by which it may be manipulated, and it is also provided with an elongated slot, k', for the passage of a screw, i, which serves, in connection with a thumb-nut, m, to secure the 25 knife in a slot or recess that is formed in or on the cloth-plate for its reception.

It is obvious that the screw i and thumb-nut m may be made in one piece, instead of 30 separate, as shown; or an ordinary set-screw, machine-screw, or other similar device may be employed, the object being to provide a simple and compact device for adjustably securing the lower or stationary knife in proper relation to the upper or movable knife.

It will be seen that the knife K can be readily withdrawn, when required, by simply detaching the clamping device. The slot or recess formed in or on the cloth-plate for the reception of the knife K is of such length as to permit the necessary endwise adjustment of said knife to or from the movable knife and at right angles therewith. The movable knife C and its actuating mechanism are also capable of adjustment to or from the stationary knife, presser-foot, and feed by means of the adjustable supporting-bracket B, as before described.

The slot or recess for supporting the adjustably-stationary knife is arranged in front of 55 the bracket B at right angles to the feed-slot p, and is separated from the rear end of said feed-slot by a narrow bridge, s, which is arranged in a line with the needle, and serves as a guide to support the edge of the fabric to be 60 trimmed, the movable knife being arranged to operate in the end of the stationary knife-carrying slot between the bridge-guide s and cutting-edge of the stationary knife. This bridge-guide may be formed integral with the cloth-plate, as shown, or in any other suitable manner.

In order to allow ample room for the vertical movement of the upper knife, C, without liability of contact between the presser-foot and the screw or devices for securing said knife to its reciprocating support, it has been found desirable to shorten the presser-foot bar t while lengthening, and making the shank of the presser-foot L with a double curve, formed as shown in Fig. 4, all danger of contact between the parts being thus avoided. The presser-foot bar t and needle-bar v are made to reciprocate vertically in apertures formed in a guide-piece, w, at the forward end or head of the goose-neck, in the usual manner.

It is obvious that the trimming devices, as above described, may be readily applied to any sewing-machine of ordinary or suitable construction.

It will be understood that I do not herein claim a knife attached to a vertically-reciprocating rod or bar, nor a vibratory lever for actuating said knife-carrying rod. Nor do I claim the attachment of said lever to an adjustable support, such construction being shown in my application filed August 12, 1882, Serial No. 69,166.

Having thus described my invention, what I claim as new, and desire to secure by Letters Patent, is—

1. In a sewing-machine trimmer, the combination, with the cloth-plate and stationary cutter, of an adjustable bracket supporting a vertically-reciprocating rod or bar and its operating mechanism, a knife or cutter detachably secured to the lower end of said rod or bar, and means for adjusting the supporting and operating mechanism of said knife to compensate for wear of its cutting-edge, substantially as described.

2. In a sewing-machine trimmer, the combination of a stationary knife or cutter capable of adjustment in or on the cloth-plate, a bracket adjustable on said plate, a vertically-reciprocating rod or bar supported in a sleeve or casting attached to the bracket, a knife or cutter carried by said vertically-moving bar, a vibrating lever pivoted to an arm of the adjustable bracket, said lever being connected at one end to the knife-carrying rod or bar, and at its opposite end to some moving part of the machine, and means for raising and lowering one end of said lever, whereby the position of the movable knife is adjusted vertically and horizontally with relation to the stationary knife, substantially as described.

3. In a sewing-machine trimmer, the combination, with the feeding, stitch-forming, and cutting mechanism, of a presser-foot having an elongated and doubly-curved shank attached to a short presser-foot bar, as described, whereby the upper movable knife may be adjusted and operated without coming in contact with said presser-foot shank, substantially as described.

4. In a sewing-machine trimmer, the combination, with the slotted or recessed cloth-plate

A, having a guide, *s*, arranged parallel with and between the feeding and cutting mechanism, of the presser-foot *L*, movable knife *C*, and a stationary knife, *K*, having an elongated slot, *k'*, screw *i*, and thumb-nut *m*, whereby said stationary knife is capable of being adjusted or withdrawn, substantially as described.

5 5. In a sewing-machine trimmer, the combination of the cloth-plate *A*, stationary knife *K*, adjustable bracket *B*, having an arm, *c*, supporting a slotted sleeve or casing, *d*, the vertically-reciprocating rod or bar *e*, arranged in said casing and carrying a knife, *C*, the vibratory lever *D*, link *f*, slotted segment or connection *F*, bracket-lever *G*, and means for adjustably securing the segmental connection, whereby the position of the movable knife and its supporting and operating mechanism is varied, substantially as described.

6. In a sewing-machine trimmer, the combination of the cloth-plate *A*, adjustable bracket *B*, vertically-reciprocating rod or bar *e*, knife *C*, attached thereto, stationary knife *K*, presser-foot *L*, guide *s*, vibratory lever *D*, adapted to actuate the movable knife, suitable feeding and stitch-forming mechanism, and means for adjusting the trimming devices, whereby the fabric may be simultaneously stitched and trimmed, substantially as described.

10 15 In testimony whereof I affix my signature in presence of two witnesses.
